UNITED STATES PATENT OFFICE.

LEON INGRASSIA, OF ASTORIA, NEW YORK.

LOCKING CLIP.

Application filed August 4, 1926. Serial No. 126,953.

The present invention relates to new and useful improvements in clips, and it pertains more particularly to that class of clips employed by hair dressers in connection with 5 appliances for permanently waving hair.

Among the several objects of the invention are to provide a clip which will securely grip an article to which it may be applied without injury thereto; to provide a clip 10 which in its attachment to an article will be self-locking; to provide a clip which may quickly and easily be detached from an article to which it has been attached or by which it is carried; and so to construct 15 the clip that its several parts may be manufactured at small cost and readily assembled.

With the above and other objects in view, reference is had to the accompanying drawings in which—

20 Figure 1 is a view in side elevation of the improved clip in its open position;

Figure 2 is a similar view showing the clip in closed position; and

25 Figure 3 is a detail sectional view showing the manner of use of the clip.

A preferred embodiment of a clip constructed in accordance with the present invention includes two jaws 10 and 12 hinged together as by a hinge pin 14. Each jaw is 30 provided with a gripping edge, preferably of curved form, as shown at 16 and 18, respectively, in the drawings.

The jaw 10 preferably comprises two plates 20 and 22, maintained in spaced relation to each other by studs or the like 24, 26 35 and the hinge pin 14 which forms the heretofore mentioned pivot of relative movement of the jaws 10 and 12. Upon one end of the jaw 10, an operating handle 28 is provided, 40 and said operating handle is preferably formed integral with the plates 20 and 22 forming the jaw 10.

The jaw 12 is preferably formed from a single piece of material, and is provided near 45 its pivoted end with an operating handle 30, and near its free end with an operating handle 32 and each of these operating handles 30 and 32 may be formed integral with the jaw 12. Projecting from the jaw 50 12 is an arm 34, preferably of arcuate form and this arm is formed or otherwise provided with a plurality of rack teeth 36, the arm 34 being located at a point substantially midway between the ends of the jaw 12 and 55 being preferably integral therewith.

Carried by the jaw 10, and preferably

pivoted between the plates 20 and 22 upon the stud 26, is a locking lever or pawl 38 for retaining the pivoted jaws 10 and 12 in gripping position. This locking lever 38 is provided upon one end with a tooth or dog 40 for co-operation with the rack teeth 36 of the arm 34 to lock the jaws 10 and 12 in gripping position, it being obvious that the rack teeth 36 of the arm 34 engage with the tooth or dog 40 when the jaws are moved to their closed or locking position. To maintain the tooth or dog 40 normally in engagement with the rack teeth of the arm 34, a spring 42 is provided. This spring 42 may 70 be carried by the stud 24 and has one of its free ends engaging the locking lever 38 as indicated at 44 in the drawings. Movement of the locking lever 38 is limited in one direction by means of a stop 48 integral with 75 the plate 22 against which said locking lever engages.

For rocking the locking lever 38 to disengage the tooth or dog 40 from the ratchet teeth 36 on the arm 34 of the jaw 12, said 80 locking lever is provided with an operating handle 46 which occupies a position sufficiently close to the handle 30 of the jaw 12 to permit of the two being simultaneously gripped when the jaws 10 and 12 are in their 85 gripping or clamping position. Pressure of the handles 46 and 30 toward each other rocks the locking lever 38 to disengage the tooth or dog 40 and at the same time effects the movement of the jaws 10 and 12 to their 90 open position.

When used in connection with permanent waving apparatus, after the chemical containing pad B and the paper tube C have been placed about the coiled strand of hair, which latter is designated by the reference character A in Figure 3 of the drawings, which is common procedure in the practice of the ordinary method of imparting a permanent wave to the hair, the end of the paper tube 100 adjacent the scalp is gripped and closed by means of the clip in the following manner: If the clip be in its closed condition, the two operating handles 30 and 46 are grasped in one hand of the operator and sufficient pressure exerted thereon to cause the locking lever 38 to release the jaw 12, whereupon the jaws 10 and 12 move to their open position shown in Fig. 1. The clip is then passed about the end of the tube C which is adjacent to the scalp and pressure then applied to the operating handles 28 and 32, for ex- 105 110

ample, by the other hand of the operator, thus moving the jaws 10 and 12 to gripping position as shown in Figures 2 and 3.

Upon movement of the jaws to the closed or gripping position, the tooth or dog 40 of the locking lever 38 will engage with the rack teeth 36 and lock the jaws 10 and 12 in their tube-gripping position until released by the operator applying pressure to the operating handles 30 and 46 in the manner heretofore described.

From the foregoing it will be apparent that the present invention provides a new and improved clip which may be applied to and removed from operative position with facility and without injury to the hair which is being treated. While in this application one embodiment of the invention has been illustrated, it is to be understood that the invention is not limited thereto, and that it may be embodied in other forms which come within the scope of the appended claims.

What is claimed as new is:

25 1. A clip of the type described comprising two gripping members pivotally connected together and movable toward each other into gripping position, means for locking the clip in its closed gripping position, 30 and separate means for simultaneously releasing said locking means and moving said members to their open position.

2. A clip of the type described comprising two members pivotally connected together between their ends, an operating member carried by each of said members and arranged in juxtaposition upon one side of the pivotal connection of the members when they are assembled, said operating 40 means serving to move the members to closed position, locking means for securing the members in closed position, an operating member carried by said locking means, an operating member carried by one of said 45 pivoted members and arranged in juxtaposition to the operating member of the locking means on the opposite side of the pivotal connection with respect to the first mentioned operating members, said second mentioned operating members adapted when moved toward each other simultaneously to release the locking means and to move the pivoted members to open position.

3. A clip of the type described comprising a pair of jaws pivotally connected together, an operating handle carried by each of said jaws and serving when moved toward each other to move the jaws to closed or gripping position, and operating handles 55 independent of said first mentioned operating handles and serving when moved toward each other to move the jaws to open or releasing position.

4. A clip of the type described comprising a pair of jaws pivotally connected to-

gether, an operating handle carried by each of said jaws and serving when moved toward each other to move the jaws to closed or gripping position, means for locking said jaws in their closed or gripping position and operating handles independent of said first mentioned operating handles for simultaneously releasing said locking means, and moving the jaws to open or releasing position.

5. A clip of the type described comprising a pair of jaws, means for pivotally connecting said jaws together, an operating handle carried by each of said jaws, an operating handle carried by one of said jaws and arranged upon the opposite side of the pivotal point of the jaws with respect to the first mentioned operating handles, locking means for holding said jaws in closed or gripping position, and an operating handle associated with said locking means and adapted for co-operation with the second mentioned operating handle for simultaneously releasing said locking means and moving said jaws to their open or releasing position.

6. A clip of the type set forth, comprising two gripping jaws, means for pivotally connecting said jaws together, a pair of operating handles associated with said jaws on one side of their pivotal point and serving when gripped to move the jaws to closed or gripping position, and a second pair of operating handles arranged upon the opposite side of the pivotal point of said jaws and serving when gripped to move the jaws to open or releasing position.

7. A clip of the type described, comprising a pair of gripping jaws, means for pivotally connecting said jaws together, a plurality of operating handles adapted when grasped to move the jaws about their pivotal point to closed or gripping position, interengaging means carried by said jaws for retaining them in their closed or gripping position, and a second pair of operating handles adapted when grasped to release said interengaged jaw-retaining means and simultaneously move said jaws to their open or releasing position.

8. A clip of the class described, comprising gripping jaws hinged at one side of their gripping edges, a ratchet carried by one of said jaws and a pawl carried by the other, arranged to co-operate to lock said jaws at the other side of the gripping edges, a release handle carried by the pawl and a co-operating handle carried by the other jaw, arranged when moved toward each other, first to release the lock and then to move the jaws toward open position.

9. A clip of the class described comprising a pair of gripping jaws hinged at one side of their gripping edges, handles on their free ends for moving the edges into

- gripping position about their hinged joint, locking means located between the handles and the hinge and comprising a dog carried by one member and co-operating recesses 5 formed in the other for engagement by the dog, and a second pair of handles, one carried by said dog and the other carried by the other gripping member, so located that movement of said handles toward each other 10 serves first to move the dog into releasing position and then to move said jaws into their open position.
10. A clip of the class described, having two jaws hinged together at one side of the 15 point of engagement with the object to be gripped, co-operating means carried by said jaws on the side of the object to be gripped remote from the point at which they are hinged together for locking said jaws in 20 gripping position, handles carried by the respective jaws and forming with said jaws first-class levers about the hinge for opening said jaws, one of said handles constituting a part of the locking means and having 25 an initial lock releasing movement.
11. A clip of the class described comprising a pair of jaws hinged at one side of their gripping edges, co-operating locking means carried by the respective jaws and 30 adapted to lock the edges together at the other side of the gripping edges, the locking means of one of said jaws being pivoted and provided with a handle, the other jaw being provided with a co-operating handle so 35 located with respect to the clip hinge that movement of said handles toward each other simultaneously releases the lock and opens the clip.
12. A clip of the type described comprising 40 two gripping members pivotally connected together and movable toward each other into gripping position, a rack carried by one of said gripping members, a tooth or dog carried by the other of said gripping members and adapted for engagement with 45 one of the teeth of said rack for locking said members in their closed gripping position, an operating handle associated with one of said gripping members and means associated with said tooth or dog and operable 50 simultaneously with said operating handle to release said locking tooth or dog and move the gripping members to open position.
13. A clip of the type described comprising two gripping members pivotally connected together and movable toward each other into gripping position, a rack carried by one of said gripping members, means carried by the other gripping member and having engagement with said rack when 55 the gripping members are moved to their closed gripping position to provide a locking means for retaining said gripping members in their closed gripping position, and operating means associated with each of 60 said gripping members and operable simultaneously to effect a release of the locking means and move the gripping members to 65 their open position.
14. A clip of the type described, comprising pivotally connected gripping members movable toward each other to gripping position, interengaging means carried by said gripping members for retaining them in 70 their closed gripping position, and means comprising an operating handle associated with one of the gripping members, and an operating handle associated with said interengaging means, and movable toward each other to effect a release of the interengaging 75 means and simultaneously move the gripping members to open or releasing position.
- Signed at New York, N. Y., this 30th day of July, 1926.
